UNITED STATES PATENT OFFICE

2,263,488

SHOE SUPPORTING JACK

Garrett P. S. Cross, Beverly, Mass., assignor to
 United Shoe Machinery Corporation, Borough
 of Flemington, N. J., a corporation of New
 Jersey

Application June 28, 1940, Serial No. 342,967

31 Claims. (Cl. 12—127)

The present invention relates to shoe supporting jacks and is intended primarily as an improvement in the type of jack disclosed in applicant's prior Patents Nos. 2,056,713 and 2,056,714, dated October 6, 1936.

This type of jack is designed to support a lasted shoe while being operated upon by the shoe making instrumentalities of various shoe making machines and more particularly automatic machines, in which means are provided for relatively moving the jack and operating instrumentalities to transfer the point of operation along the shoe and for controlling the relative positions of the shoe and operating instrumentalities during such transfer.

It is to be understood, however, that the several features of the present invention, except as hereinafter specifically defined in the claims, are not confined to any particular type of jack nor limited to use in any particular kind of shoe making machine.

The objects of the present invention are to facilitate the speedy and accurate location of a lasted shoe on the jack regardless of the size or style of the shoe and the clamping of the shoe firmly in adjusted position so as to prevent displacement on the jack during the shoe making operation while leaving all necessary portions of the shoe exposed to the action of the instrumentalities of the particular machine in which the jack is used.

With the above objects in view, a feature of the present invention has been embodied in a shoe supporting jack provided with toe centering grips or clamps similar to those disclosed in applicant's prior patents but constructed and arranged to also act as a support for the toe portion of the shoe. To this end, the toe grips are shaped to extend around the last supported upper a sufficient distance to support the toe portion of the shoe at the desired height. In accordance with another novel feature of these toe grips, they are mounted in the jack so as to be capable of relative movement heightwise of a shoe placed on the jack to compensate for differences in the height of the last at opposite sides of the shoe.

Other novel features of the grips are their supporting means which permits them to be moved to the proper supporting position by contact with the shoe as it is placed on the jack, and the means for locking the grips against separation after being brought against the sides of the shoe, and for locking them in the heightwise

position to which they are moved in placing a shoe on the jack.

Another feature of the present invention contemplates the provision in a shoe supporting jack of means for determining the plane transversely of the shoe in which the thread surface of the sole of a shoe supported on the jack will be located comprising leveling devices arranged to engage the under surface of the projecting shoe sole at opposite sides of the shoe. This feature has been embodied in a construction comprising leveling devices in the form of vertical pins which are yieldingly mounted in the toe supporting portion of the jack and are arranged to be depressed in unison as the shoe is forced downwardly by the operator to bring the toe of the shoe into engagement with the toe rest. The leveling pins are also mounted so as to be movable towards and from each other and this movement of the leveling pins, in the illustrated construction, is utilized to move the toe grips into engagement with the shoe.

In order to prevent possible interference with the operating devices of the machine in which the jack is used, a feature of construction relating to the leveling devices comprises means for withdrawing the leveling devices from contact with the shoe heightwise of the last after the shoe has been clamped in position on the jack. As has been stated, in the illustrated construction, the leveling devices are utilized to move the toe grips into engagement with the sides of the shoe. In order to permit the leveling pins to be readily withdrawn, the inward pressure of the pins towards the shoe is relieved after the toe grips have been locked in position and prior to the withdrawal of the pins. In this connection, it may be noted that the illustrated jack is provided with a toe gage to limit the lengthwise movement of the shoe in being applied to the jack and that this toe gage is likewise withdrawn heightwise of the last after the shoe is clamped in position. As a convenient means for withdrawing the toe gage, it is connected to be operated through the same mechanism which withdraws the leveling devices.

Other features of the present invention relate to an improved construction and arrangement for tipping the last pin upon which the heel portion of the lasted shoe is supported and at the same time bodily moving the support for the last pin to press the toe of the shoe firmly against the toe rest in clamping the shoe in position. The shoe supporting jack, in which the features of the present invention have been embodied, is pro-

vided with a jack frame carrying a toe rest and with a heel supporting arm mounted on the jack frame to move towards and from the toe rest. In applying a shoe to the jack, it is placed upon a last pin pivotally mounted on the heel supporting arm and the arm is moved towards the toe support to locate the shoe lengthwise on the jack. After being so located, it is clamped in position and in accordance with a feature of the present invention, the clamping means comprises means for tipping the last pin in a direction to force the toe of the shoe against the toe rest and for simultaneously moving the arm on which the last pin is mounted away from the toe rest, the combined movements acting to press the toe of the shoe firmly against the rest without producing any appreciable longitudinal movement of the shoe. By moving the arm on which the last pin is mounted away from the toe rest during the tipping movement of the last pin, the shoe as a whole is caused to swing about a center a substantial distance above the pivotal support for the last pin and thus the toe of the shoe is not advanced on the jack but is pressed directly downward.

The jack in which the several features of the present invention have been embodied, in addition to the features above referred to, also embodies many novel features of construction and arrangement including novel mechanism for actuating the various parts and means whereby a free movement of the heel supporting arm towards the toe rest to locate the shoe longitudinally is permitted and thereafter relative movement of the heel support and toe rest is prevented and the mechanism by which the various parts of the shoe clamping mechanism are actuated is rendered operative. The advantages of these, and other novel features, as will hereinafter appear, will be obvious to those skilled in the art from the following description taken in connection with the accompanying drawings, in which Fig. 1 is a view in side elevation of a shoe supporting jack embodying the several features of the invention, the jack illustrated being designed for use in an automatic sole trimming machine; Fig. 2 is a view in side elevation on an enlarged scale of the upper end of the toe supporting portion of the jack; Fig. 3 is a view in end elevation of the parts illustrated in Fig. 2; Fig. 4 is a view similar to Fig. 2, but with portions of the jack frame removed and broken away to show underlying parts; Fig. 5 is a view in end elevation, similar to Fig. 3, but with the end plate of the toe supporting portion of the jack removed, together with the parts supported thereby, and with certain parts shown in section; Fig. 6 is a view in end elevation of certain of the parts illustrated in Fig. 5, many of the parts in Fig. 5 being omitted to show more clearly the shoe supporting toe grips, together with their supporting and locking mechanism; Fig. 7 is a view in side elevation, partly in section, of the mechanism illustrated in Fig. 6; Fig. 8 is a detail sectional view taken on the line 8—8 of Fig. 6; Fig. 9 is a detail sectional view taken on the line 9—9 of Fig. 6; Fig. 10 is a view in end elevation of a portion of the mechanism illustrated in Fig. 5, illustrating particularly the leveling pins, together with their supporting and actuating means; Fig. 11 is a view in side elevation, partly in section, of the mechanism illustrated in Fig. 10; Fig. 12 is a view in sectional elevation of the mechanism illustrated in Fig. 5, the section being taken on a vertical plane passing substan-

tially through the leveling pins and the locking plunger for the toe grips; Fig. 13 is a view in end elevation of the lower end of the toe supporting portion of the jack; Fig. 14 is a view in side elevation of the parts illustrated in Fig. 13, with the frame of the machine broken away to show underlying parts, the mechanisms being illustrated in the positions assumed before a shoe is placed on the jack; Figs. 15, 16 and 17 are views similar to Fig. 14 illustrating the positions which the mechanisms assume at different stages in the operation of clamping a shoe on the jack; Fig. 18 is a detail perspective view of a portion of the mechanism illustrated in Fig. 14, certain of the parts being separated to more clearly illustrate the construction and arrangement; Fig. 19 is a sectional plan view taken substantially on the line 19—19 of Fig. 12; Fig. 20 is a view in side elevation of the upper end of the heel supporting portion of the jack; Fig. 21 is an end view of the construction illustrated in Fig. 20 looking towards the right; Fig. 22 is a plan view of the parts illustrated in Figs. 20 and 21; and Fig. 23 is a vertical sectional view illustrating in sectional side elevation the parts shown in dotted lines in Fig. 20.

The jack illustrated in the drawings comprises a frame 2 which carries at its upper end the toe supporting devices or rest hereinafter described. At its lower end, the jack frame is mounted, as is customary in automatic machines of the type for which the jack was particularly designed, upon a supporting arm 4. The connection between the arm and the jack frame consists of a rotatable pulley 6 mounted on the arm, through which pulley the spindle at the lower end of the frame extends, and to which it is pivotally connected by a gimbal joint of suitable construction. Near the lower end of the jack frame is pivotally mounted a heel supporting arm 8 which is adapted to swing towards and from the toe supporting portion of the jack to locate a shoe placed on the jack in the desired longitudinal position. To support the heel portion of a shoe placed on the jack, the heel supporting arm is provided at its upper end with a pivotally mounted last pin 10 adapted to enter the usual last pin hole in the last. Suitable mechanism is mounted in the jack for tipping the last pin so as to press the toe of the shoe against the toe rest after the shoe has been located longitudinally on the jack and also connections are provided between the heel supporting arm and the toe supporting portion of the jack to hold the arm in the position to which it has been moved in locating the shoe. In order to enable the jack to receive long legged boots or shoes with high vamps, the heel supporting arm is formed with front and rear portions extending heightwise of the last of a shoe placed on the jack and separated sufficiently to provide an opening between them to receive the boot leg or high shoe upper.

When the parts of the jack are in open position ready to receive a shoe, the heel supporting arm is freely movable towards and from the toe rest, its movement in each direction being limited by slots 12 in the downwardly and forwardly extending flanges of a plate 14 pivotally mounted upon the rear portion of the heel supporting arm 8, the flanges of which plate extend on opposite sides of the frame 2 of the jack and the slots 12 of which are engaged by pins 16 projecting from the jack frame. This plate 14, in addition to limiting the movements of the

heel supporting arm, also forms a guide or guard to direct a boot leg or high upper into the opening between the front and rear portions of the heel supporting arm.

When a shoe is placed on the heel supporting arm and the arm is moved towards the toe rest, the movement of the arm is limited by contact of the toe of the shoe with a toe gage indicated at 18 and comprising a vertically arranged plate mounted on the front surface of the upper end of the jack frame 2.

The means for locking the heel supporting arm in the position to which it is moved to bring the toe of the shoe against the toe gage 18 comprises a slide 20 (see Figs. 1 and 14) which is pivotally mounted at its rear end in the rear portion of the heel supporting arm and extends forwardly into the frame 2 of the jack. A rack indicated at 22 is formed on the lower side of the slide 20 and is arranged to cooperate with a segmental rack 24 formed on a rack carrying member 26 mounted in the jack frame. During the movement of the heel supporting arm towards the toe rest, the rack 22 is held out of engagement with the rack 24 by means of a compression spring 28 acting on a downward projection from the hub of the slide. So long as the rack 22 is held out of engagement with the rack 24, free movement of the heel supporting arm towards and from the toe rest is permitted. After the shoe has been located in the desired longitudinal position by contact with the toe gage 18, the slide 20 is depressed to bring the racks 22 and 24 into engagement by means hereinafter described.

The means for supporting the last pin 10 on the heel supporting arm 8 comprises a last pin supporting block 28, see Figs. 1 and 20 to 23, pivotally mounted on a horizontal pivot pin 30 secured in the arm 8, the arrangement being such that a pivotal movement of the block 28 about the pin 30 tips the last pin 10 in a direction to force the toe of the shoe against the toe rest of the jack. As was stated in the introductory part of the specification, the illustrated jack is provided with leveling devices arranged to engage the under surface of the projecting shoe sole at opposite sides of the shoe and thus determine the plane transversely of the shoe in which the tread surface of the sole will be located. To enable these leveling devices to operate satisfactorily regardless of the position of the last pin hole with relation to the bottom of the last, the last pin 10 is mounted on the block 28 so as to be capable of accommodating itself to the position to which the last pin hole is moved in bringing the tread surface of the shoe sole into the desired transverse plane. To this end the last pin projects from a base which is provided with a downwardly and forwardly extending pivot pin 32 having a bearing in the block 28. As illustrated in the drawings, see particularly Figs. 1 and 20, the axes of the last pin 10 and pivot pin 32 are located with relation to each other so as to intersect at substantially the heel seat of a last placed on the jack. To hold the last pin on the block 28, while permitting its ready removal, a latch 34 actuated by a spring 35 is provided pivotally mounted in the block 28 and arranged to engage a notch in the rear side of the pin 32.

After the shoe has been brought to the desired longitudinal position on the jack, the last pin is locked against movement with relation to the supporting block 28 by means of a locking

lever 36, mounted in the block 28 on the pivot pin 30, the upwardly extending arm of which lever is provided with a series of notches arranged to engage a corresponding series on the rear edge of the base of the last pin. After the shoe is in the desired longitudinal position, the last pin is also locked against backward tipping movement and to accomplish this result, the same lever 36 is utilized which locks the last pin to its supporting block. To enable the lever 36 to lock the block 28 against backward tipping movement, the lever is pivotally mounted in the block. To actuate the lever 36, its horizontally extending arm is connected by a link 38 (see Figs. 1 and 23) to the horizontal arm of a bell crank lever 40 mounted in the lower portion of the heel supporting arm 8. The vertical arm of the bell crank 40 is connected by a link 42 to an arm 44 pivotally mounted at its lower end on a pivot shaft forming the pivotal connection between the heel supporting arm 8 and the frame 2 of the jack. The arm 44 extends upwardly within the frame of the jack and at its upper end is provided with a rack 46 (see Figs. 1 and 14). It will be obvious from an inspection of these figures that a tipping movement imparted to the block 28 by the operator in forcing the shoe against the toe rest and also a movement of the heel supporting arm 8 towards the toe rest will impart a forward swinging movement to the arm 44, the lever 36 during these movements being held stationary with relation to the block 28 by contact of an adjusting screw 48 in the downwardly extending arm of the lever with a pin 50 in the block 28 and by the spring 35 which forms a yielding connection between the block 28 and the lever 36. It will also be obvious that a forward swinging movement imparted to the arm 44 while the heel supporting arm 8 is held against movement will first swing the block 28 and lever 36 as a unit on account of the connecting spring 35, thus forcing the forward end of the shoe downwardly upon the leveling devices and causing the last pin 10 to rock about the pivot pin 32 to the desired position before engagement of the lever with the base of the last pin. Continued movement of the arm 44 acting on the lever 36 through the connections including the link 38 causes the spring 35 to yield and the lever 36 to engage the base of the last pin. After this, the block 28 and lever 36 again swing as a unit and tighten the shoe against the toe rest.

While the shoe is being moved to its desired longitudinal position, the arm 44 is free to swing. After the shoe is in position, the arm 44 is locked against backward movement by a rack 52 which is brought into mesh with the rack 46 after the meshing of the racks 22 and 24 which hold the heel supporting arm 8 against movement. The rack 52 is formed on the lower portion of the rack carrying member 26 and is brought into engagement with the rack 46 by a downward bodily movement of the rack carrying member. The rack carrying member 26 is mounted on a horizontal pivot shaft 54 in the machine frame so as to be capable of a bodily vertical movement as well as an oscillating movement and while the parts of the jack are in open position to receive a shoe, is held yieldingly in raised position and at the limit of its movement in a clockwise direction, as viewed in Fig. 14, by means of a tension spring 56 stretched between a pin 58 on the jack frame and a pin 60 on the rack carrying member 26 near the rear end of the

rock 52. The spring 56 is arranged to act on the member 26 at one side of the shaft 54, as indicated in Fig. 14, and while the member 26 is not engaged by the racks 22 and 46, the spring tends to move the member 26 in a clockwise direction until the spring is stretched to some extent around a pin 62 on the jack frame. With the parts in the position indicated in Fig. 14, the member 26 is thus yieldingly held by the spring 56 in a position of equilibrium from which it can be readily moved in either direction. It is to be noted that the radial distance of the rack 24 from the center of the shaft 54 is several times less than the radial distance of the rack 52 from the center of the shaft. It is also to be noted that the racks 22 and 24 are brought into mesh prior to the meshing of the racks 46 and 52. The racks 22 and 46 are brought into mesh with the racks 24 and 52 of the member 26 after the shoe has been located in the desired longitudinal position on the jack. At this time, the teeth of the racks 22 and 24 may not be exactly in alignment and accordingly, when the racks 22 and 24 are brought into engagement, a movement of rotation in one direction or the other may be imparted to the member 26. At this time, the member 26 is free to move and accordingly, the racks may be brought into mesh without producing any movement of the slide 20 and through the slide a displacement of the shoe on the jack. After the racks 22 and 24 are in engagement, the teeth of the racks 46 and 52 may be out of alignment and accordingly as these two racks are brought into engagement, a movement in one direction or the other will be imparted to the member 26. This movement, however, will be not over the length of half a tooth of the racks 46 and 52 and by reason of the different radial distances of the racks 52 and 24 from the center of the shaft 54, will produce a much less and substantially inappreciable movement of the racks 24 and 22. Rack teeth of a size to afford the desired strength and rigidity can therefore be employed in the construction and arrangement of parts illustrated without interference with the desired nicety in the location of the shoe on the jack. Depression of the slide 20, as hereinafter described, to bring the racks 22 and 24 into mesh, imparts a bodily downward movement to the rack carrying member 26 and causes the rack 52 to mesh with the rack 46. Simultaneously with the meshing of these racks, the rack 52 near its forward end is brought into mesh with a pinion 64 mounted to rotate on a cross shaft 66 mounted in the jack frame to which shaft is secured a ratchet toothed segment 68 engaged by a spring-pressed locking pawl 70. In the final operation of clamping the shoe on the jack, a rotary movement is imparted to the pinion 64 from a manually actuated jacking lever 72, as will be hereinafter described. This rotary movement swings the arm 44 with its attached rack 46 in a direction to swing the lever 36 so as to lock the last pin to its supporting block 28 and thereafter tilt the block on the heel supporting arm so as to force the toe of the shoe firmly against the toe rest. Simultaneously with this clamping, tipping movement of the last pin, a bodily backward movement is imparted to the heel supporting arm 8 through the rack carrying member 26 and slide 20, which movement tends to still further tip the last pin and increase the pressure of the toe against the toe rest.

For the performance of certain operations on a shoe and with certain styles of last, it is desirable to locate the tread surface of the shoe or the bottom of the last in a transverse plane determined by the location of the last pin hole in the last. Accordingly, in the illustrated construction, means are provided for locking the last pin permanently to its supporting block 28, this means consisting of the adjustable set screw 48 which bears against the pin 50 and which may be adjusted so as to force the notched end of the lever firmly into engagement with the notches in the base of the last pin. To hold the pin securely in any desired adjusted position, a spring 74 is coiled around the set screw and is arranged to bear frictionally at one end against the lever 36 and at the other end against the head of the screw. The toe centering grips or clamps which also act as a toe rest are similar in construction and each comprises a base portion 76, see Figs. 5, 6 and 7, shaped and arranged to extend beneath the toe portion of a shoe a sufficient distance to form a toe rest and a portion 78 shaped and arranged to engage the side of the shoe. The base portions 76 are in the form of blocks and are pivotally mounted on the upper ends of supporting levers 80, the pivots for the block extending lengthwise of the shoe to permit the grips to swing so as to bring the toe supporting portion and the side engaging portion in contact with the shoe upper. To enable the side engaging portions 78 to conform to the longitudinal curvature of the lasted shoe, they are pivotally mounted in the base portions 76 to swing about axes inclined downwardly towards each other transversely of the shoe. There are two levers 80 for supporting each toe grip, the block 76 of each grip being mounted between the upper ends of a pair of levers 80. At their lower ends, the levers 80 are pivotally connected to the arms of a transverse supporting yoke 82 which is pivotally mounted midway between its ends by means of trunnions 84 extending from the yoke into bearings in the vertical plates 86 and 88 forming a portion of the upper end of the jack frame 2. This arrangement of the parts for supporting the toe grips permits the grips to move outwards and from each other as the levers 80 swing about their pivotal connections with the yoke 82 and also permits the toe grips to move heightwise of the last with relation to each other to compensate for variations in the height of the toe portion of the last as the toe of the shoe is pressed downwardly against the toe grips. During this relative movement of the toe grips, the yoke 82 is rocked on its trunnions and equal movements are imparted to the toe grips in opposite directions. The toe grips are moved into engagement with the sides of the shoe by the movement of the leveling pins towards each other, as hereinafter described, and in order to lock the toe grips in firm engagement with the shoe, after being so moved, a locking slide 90 is connected to each pair of levers 80. Each slide 90 projects from a plate 92 which extends between the levers 80 and is provided with outwardly projecting ears by which it is pivotally connected to the levers. At their inner ends, the slides 90 are received in a guideway extending transversely through the upper end of a frame 94, which is supported by the slides and is mounted so as to be capable of a swinging movement by means of a pin 96 extending transversely to and above the guide-

way for the slides 90. The pin 96 is mounted to turn in bearings in the plates 86 and 88 of the jack frame and is slotted on opposite sides to receive ears projecting upwardly from the frame 94 and to form a flat web portion received in a vertical slot between the upwardly projecting ears of the frame 94. This construction permits the frame 94 to swing on the pivot pin 96 when the side grips move relatively to each other heightwise of the last and also permits the frame 94 to move in a direction heightwise of the last as the toe grips are moved towards and from each other. To permit this movement of the frame 94 heightwise of the last, a cross semi-cylindrical recess is formed in the pin 96, as indicated in detail in Fig. 8.

The locking slides 90 are semi-cylindrical in cross-section, as best shown in Fig. 8, and are arranged with their inner ends overlapping in the guideway of the frame 94. The opposing faces of the slides are arranged at an angle to each other to form a V-shaped notch and these faces are provided with teeth arranged to cooperate with corresponding teeth formed on the upper wedge-shaped end of a locking plunger 98 mounted in the frame 94. When the plunger 98 is in its lowest position, it is out of engagement with the locking slides 90 and the toe grips are free to move towards and from each other, but when the plunger is in its highest position, the toe grips are held locked in firm engagement with the shoe. The locking plunger 98 is pressed downwardly by a coiled spring 100 seated in a recess in the plunger and bearing at its upper end against a cross pin 102 mounted in the frame 94. The pin 102 (see Fig. 9) is provided with a cross slot to receive the upper end of the spring 100 and can be removed by turning the pin until the cylindrical portion of the pin compresses the spring and then pushing the pin endwise.

The locking plunger 98 is forced upwardly into engagement with the locking slide 90 by means of a sliding wedge 104 interposed between a roll 106 at the lower end of the frame and the wedge-shaped arm of a bell crank 108 which extends between the wedge 104 and the lower end of the plunger 98. The bell crank 108 is pivotally mounted upon a pin 110 in the jack frame and as the wedge 104 is moved endwise the wedge-shaped arm of the bell crank 108 is swung upwardly into engagement with the lower end of the plunger 98 and during its continued upward movement forces the plunger 98 upwardly into engagement with the locking slide 90. The lower end of the locking plunger 98 and the upper surface of the wedge-shaped arm of the bell crank 108 are provided with corresponding teeth and thus the wedge-shaped arm also serves to lock the frame 94 from swinging movement in either direction about the pivot pin 96. It will be obvious that the locking of the frame 94 from swinging movement locks the toe grips in the positions to which they have been moved with relation to each other heightwise of the last. The mechanism for actuating the wedge 104 will be hereinafter described. To prevent possible contact of the inner ends of the slides 90 with the plates 92 carried by the levers 80, each of the plates 92 is provided with an opening, as indicated in Figs. 7 and 12, in line with the locking slides 90 carried by the opposite plate 92.

The leveling pins (see Figs. 4, 5, 10, 11 and 12) are indicated at 112. They are mounted to

slide vertically in carriers 114 and are located in a transverse plane passing through the toe centering grips. Each carrier is pivotally mounted at the upper end of an actuating lever or frame 116 by means of which the carriers with the leveling pins are moved towards and from each other. At its upper end, each lever 116 fits between the upper ends of a pair of levers 80 on which a toe centering grip is mounted, as best shown in Fig. 4, and at its lower end, each lever 116 is forked and provided with pivotal bearings in the front and rear plates 86 and 88 of the jack frame. At their lower ends, the levers 116 are provided with inwardly extending overlapping portions indicated particularly in Figs. 5 and 10 which are slotted to receive a pin 118 which passes through the slots and is mounted in the upper end of a vertical link 120. The levers 116 are thus connected together so that when actuated, they move equal distances towards and from each other. At its lower end, the link 120 is connected to actuating mechanism hereinafter described. To maintain the pins 112 in parallel relation to each other as they are moved towards and from each other, each carrier 114 is provided with an inwardly projecting arm overlapping the corresponding arm on the other carrier and these arms are provided with slots indicated at 122 through 30 which pass cylindrical rods 124 which are mounted in and extend between the vertical plates 86 and 88 of the jack frame. Each rod 124 accurately fits a slot 122 and the shape of the slots is such that during the swinging movements 35 of the levers 116 to move the carriers towards and from each other, the carriers swing on their pivotal connections with the levers 116 sufficiently to preserve the parallel relation of the leveling pins.

40 In the illustrated construction, the mechanism for moving the leveling pins 112 towards and from each other is also utilized to bring the toe centering side grips into engagement with the shoe. To accomplish this result, the pins are arranged to bear against the base portions 76 of the side grips and to pass upwardly through notches formed in the upper ends of the side engaging portions 78 of the grips. A spring 125 coiled around the opposite ends of a hub of each 45 base portion 76 and extending around the upper end of a carrier 114 with its ends in engagement with an under surface of the base 76 serves to hold the grip in contact with the pin while permitting a slight movement of separation for a 50 purpose hereinafter explained.

The leveling pins 112 are yieldingly supported in the carriers 114 and are connected so as to be moved equal distances when depressed by the engagement with their upper ends of the under 55 surface of the sole of a shoe applied to the jack. To cause the pins to be moved in unison, each pin at its lower end is provided with a cross slot engaged by the T-shaped end of a lever arm 126 (see Figs. 4, 12 and 19) secured to a rock shaft 128 mounted in the jack frame. To the shaft 128 is also secured a downwardly extending arm 130 which is connected by means of a link 132 to a lever 134 mounted in the jack frame and acted upon by a spring 136 connecting one end 60 of the lever with a pin on the jack frame. With this construction, the pins 112 are yieldingly supported and are caused to move in unison whenever they are actuated.

The levers 116 are actuated to move the leveling pins 112 towards and from each other by con-

nections from the jacking lever 72. These connections comprise a floating lever 138 one end of which is pivotally connected at 140 to the lower end of the link 120 and the other end of which is pivotally connected at 142 to a link 144 forming part of the connections for actuating the locking devices for the toe grips, as will presently be described. The floating lever 138 is pivotally connected midway between its ends to the upper ends of a pair of links 146 which are pivotally connected at their lower ends to one end of an oscillatable and bodily movable lever 148 the other end of which is connected by means of a link 150 to an arm 152 secured to the shaft 66, to which shaft the jacking lever 72 is also secured. The link 144 at the opposite end of the lever 138 from the link 120 is pivotally connected at its upper end with the arm of a toothed segment 154 mounted in the lower end of the vertical arm of the bell crank 108 and meshing with a rack on the sliding wedge 104. A spring 156 is connected between a pin 158 on the jack frame and a point on the lever 138 between the pivotal connection 140 with the link 120 and the pivotal connection of the links 146 with the lever. This spring exerts an upward pull on the lever 138 tending to swing the lever in a counterclockwise direction, as viewed in Figs. 5 and 10, about the pivotal connection of the lever with the links 146. The leveling pins 112 are thus supported so that they can be moved to some extent towards and from each other by the operator in placing a shoe on the jack, the inward and outward movements of the upper ends of the levers 116 producing a vertical movement of the link 120 and an oscillating movement of the floating lever 138. During its vertical movements, the link 120 is guided by the engagement of the cross pin 118 with the slots in the lower ends of the levers 116 and by a vertical guiding slot 160 in an upwardly extending offset portion of the link (see particularly Figs. 5, 10 and 11), which is engaged by a pin 162 fixed in the plate 86 of the jack frame. The floating lever 138 is also supported at the end opposite its pivotal connection with the link 120 by a locking latch 164 pivotally mounted on the jack frame and arranged with its upper end extending beneath and bearing against the hub of the link 144. The locking latch 164 is formed with three arms projecting from a central hub, one of which arms is connected by a tension spring 166 to a pin 168 fixed in the jack frame. By means of this spring, the end of the floating lever 138 removed from the pivotal connection with the link 120 is yieldingly supported and thus permits the oscillating movement of the lever 138 about its pivotal connection with the links 146. It will be noted that the pressure of the upper end of the latch 164 against the hub of the link 144 tends to swing the link on its pivotal connection 142 in a direction to move the locking wedge 104 outwardly towards the right, as viewed in Figs. 5, 6 and 12.

When the shoe is in position on the jack, the jacking lever 72 is actuated and through the connections above described, pulls downwardly on the links 146. This downward movement at first swings the floating link 138 about its pivotal connection 142, thereby through the link 120 and levers 116 forcing the leveling pins still further towards each other and clamping the toe grips firmly against the shoe. When the inward movement of the levers 116 is stopped by the engagement of the toe grips with the sides of the shoe, continued downward movement of the links 146 swings the floating lever 138 about its pivotal

connection 140, thereby pulling down on the link 144 and swinging the gear segment 154 in a direction to move the sliding wedge 104 inwardly into locking position. As the wedge 104 moves inwardly, it swings the bell crank 108, with the wedge-shaped arm of which the upper surface of the wedge 104 is in sliding engagement, about its pivotal connection with the jack frame in a counterclockwise direction and brings the notched upper surface of the wedge-shaped arm into engagement with the notched surface at the lower end of the locking plunger 98 which, during the continued inward movement of the wedge 104, raises the locking plunger into engagement with the locking slides 90 of the toe grips and also locks the frame 94 against swinging movement, as has hereinbefore been described. As the links 146 complete their downward movement under the action of the jacking lever, locking notches 170 in the link 144 are engaged by the locking pawl 164 which has been displaced against the tension of the spring 166 during the final downward movement of the lever 138 and thereby the parts actuated from the floating lever 148 are securely locked in position.

Before the operation is started on a jacked shoe, it is desirable to withdraw heightwise of the last both the leveling pins 112 and the toe gage 18. Accordingly, the illustrated jack is provided with mechanism for effecting these results and this mechanism is constructed and arranged to be actuated from the jacking lever after the leveling pins have been moved inwardly and the toe grips have been locked in shoe clamping position. The toe gage 18 comprises a plate mounted to slide vertically on the front face of the plate 86 of the jack frame (see Figs. 3 and 4), being guided at its upper portion between the plate 86 and a block 172 bolted to the plate 86 and provided with a socket to receive the jack feeding link of the machine in which the jack is to be used. From each side of the toe gage plate, an arm extends laterally and then downwardly, one arm being provided with a slot 174 engaged by a fixed guiding pin 176 and the other arm being pivotally connected to the forward end of the lever 134 hereinbefore described as a portion of the mechanism for yieldingly supporting the leveling pins. As will be apparent from an inspection of the drawings, and more particularly Figs. 4 and 11, a movement of the lever 134 in a clockwise direction will act to withdraw simultaneously heightwise of the last both the leveling pins and the toe gage. To actuate the lever 134, a cam 178 is secured to a cross shaft 180 mounted in the jack frame and is arranged, when the shaft is rocked in a counterclockwise direction, to engage a roll on the rear end of the lever 134. To actuate the rock shaft 180, it is provided with an arm 182 which is connected by means of a link 184 to the link 150 which is actuated from the jacking lever 72, as hereinbefore described. The rock shaft 180 is actuated only during the last portion of the upward movement of the jacking lever 72 and to accomplish this result, the link 184 is pivotally connected at its upper end to the arm 182 and at its lower end is provided with a slot 186 engaged by a pin 188 projecting from the side of the link 150. The movement of the rock shaft 180 in a clockwise direction is limited by the engagement of a lug 190 on the arm 182 with a fixed portion of the jack frame.

Prior to the downward movement of the leveling pins 112, the pressure of the pins against

the sides of the shoe and against the toe grips is relieved by a partial rotation of the cross rods 124 which are provided with transverse slots indicated at 192 arranged, upon partial rotation of the rods, to receive the lower edges of the slots formed in the inwardly projecting arms of the leveling pin carriers 114. The rods are rotated at the proper time just prior to the downward movement of the leveling pins by mechanism comprising pinions 194 secured to the front ends of the rods (see Fig. 3), an oscillatable segment 196 mounted on the plate 86 of the jack frame and meshing with the pinions 194, a link 195 connected at its upper end to the segment 196, a lever 198 pivotally mounted at its rear end upon the shaft 54 and pivotally connected at its forward end to the lower end of the link 195, and a cam 200 secured to the shaft 66 and arranged to engage a roll 202 on the lever 198. A spring 204 connected between the lever 198 and a pin on the jack frame tends to hold the lever 198 in its lowest position and the construction is such that an upward movement of the lever 198 produced by the cam 200 rotates the rods 124 into their pressure relieving position. After the rods 124 are thus rotated, the only pressure of the pins 112 against the sides of the shoe or against the toe grips is the comparatively light pressure due to the springs 125 and the pins can be lowered readily without danger of injury to the shoe upper.

In the illustrated jack, the jacking lever 72 is utilized not only to press the leveling pins and side grips against the shoe and lock them in position, and thereafter withdraw the leveling pins and toe gage heightwise of the shoe, but is also utilized to depress the slide 20 to bring its rack 22 into mesh with the segmental rack 24 and thereby lock the heel supporting arm 8 in its forward position, to depress the rack carrying member 26 to bring the rack 52 in mesh with the rack 46 and with the pinion 64, and finally to rotate the pinion 64 in a direction to tip the last pin 10 in a direction to clamp the toe of the shoe against the toe rest and simultaneously move the heel supporting arm rearwardly. As has been stated, the jacking lever 72 is connected to the lever 148 through shaft 66, arm 152 and link 150. The lever 148 is in the nature of a floating lever and is provided intermediate its ends with a pin 206 projecting on opposite sides of the lever into substantially vertical slots in parallel plates 208 fixed in the jack frame on opposite sides of the lever 148 (see Fig. 18), the plates being supported at their upper ends on the rock shaft 180 and at their lower ends on a cross shaft 210 fixed in the jack frame. The pin 206 also passes through slots in upwardly and rearwardly extending parallel arms of a lever 212 pivotally mounted upon the shaft 210. When the jack is open, that is, with the heel supporting arm in its rearward position and the various parts of the jack mechanism ready to receive a shoe, the pin 206 is in the lower portions of the slots in the plates 208 and in the arms of lever 212 and these slots cross each other as illustrated in Figs. 14 and 18. So long as the lever 212 is held in the position indicated in Fig. 14, the floating lever 148 carrying the pin 206 is locked in position and the jacking lever 72, which is connected to the lever, cannot be moved. The lever 212 is held in the position indicated in Fig. 14 until the shoe has been located in the desired longitudinal position on the jack by means of a locking latch 214 pivotally mounted on the shaft 75

180 and arranged to engage a notch on the upper end of one of the slotted arms of the lever 212. The latch 214 is connected by means of a link 216 (see Figs. 2 and 4) to one arm of a bell crank 218 pivotally mounted on the jack frame, and another arm of the bell crank 218 is connected to a link 220 which extends upwardly and forwardly beneath the plane of the toe grips and projects through a slot 222 in the toe gage 18. At its forward end, the link 220 is provided with a cross head 224, see Fig. 3, which is engaged by the forward face of the toe gage 18. The toe gage is mounted so as to be capable of yielding lengthwise of the jack and is moved as the toe of the shoe is brought against it. This movement of the toe gage, acting through the link 220, bell crank 218 and link 216, raises the locking pawl 214 from the lever 212 against the tension of a spring 226 connecting the horizontal arm of the bell crank 218 with a pin on the jack frame. The jacking mechanism operated from the jacking lever 72 is thus unlocked by the movement of the shoe into the required longitudinal position on the jack.

25 The first portion of the upward movement of the jacking lever 72 is utilized to depress the slide 20 and rack carrying member 26 to thereby bring the rack 22 into mesh with the rack 24 and the rack 52 into mesh with the rack 46 and pinion 64. To accomplish this result, the lever 212 is provided, on the opposite side of the shaft 210 from the slotted arms, with a roll 228 arranged to bear against the upper side of the slide 20, and the lower portion of the slots in the arms of the lever 212 are so shaped as to cause the lever to be swung in a clockwise direction during the first portion of the upward movement of the pin 206 as the lever 148 swings about its pivotal connection with the lower ends of the links 146. This brings the parts into the positions illustrated in Fig. 15, in which it will be seen that the upper portions of the slots in the plates 208 and in the arms of lever 212 are in alignment. Continued upward movement of the pin 206 in the slots is now permitted without imparting further movement to the lever 212.

30 During the next portion of the upward movement of the jacking lever 72, the lever 148 is actuated to pull down on the links 146 and thereby move the leveling pins and toe grips into engagement with the shoe and lock these parts in position, as has been described. The bodily movement of the lever 148 to the position indicated in Fig. 15 brings a fulcrum pin 230 projecting from the lever against the hooked end of a pivotally mounted arm 232, which arm is pressed into engagement with the pin by means of a spring 234 stretched between the upper end of the arm and the jack frame. The arm 232 is pivotally mounted at its lower end at 236 upon a block 238 pivotally mounted on the lever 212, and the arm 232 is acted upon below its pivotal connection 236 by a spring-pressed plunger 240 mounted in the block 238 whereby the arm 232, in addition to a pivotal movement with the block 238, is also capable of a limited pivotal movement on the block 238 for a purpose hereinafter described. With the pin 230 engaged by the hooked upper end of the arm 232, continued upward movement of the jacking lever 72 swings the lever 148 about the pin 230 as a fulcrum, thereby pulling down on the links 146 and forcing the toe grips firmly against the sides of the shoe. In this stage in the operation of jacking a shoe, the parts reach the position indicated in Fig. 16.

During the movement of the jacking lever 72 to bring the parts to the positions indicated in Fig. 16, the pin 188 on the link 150 has traveled from the bottom to the top of the slot 186 in the link 184. Continued upward movement of the jacking lever, which movement is permitted by the swinging movement of the arm 232 about its pivotal connection at 236 with the block 238, raises the link 184 and thereby rocks the shaft 180 in a counterclockwise direction, as indicated in Fig. 17. This rocking movement of the shaft 180 causes the cam 178 on the shaft to actuate the lever 134 and withdraw the leveling pins and toe gage as hereinbefore described. As the jacking lever 72 completes its upward movement, the pinion 64 is rotated so as to turn the rack carrying member 26 in a counterclockwise direction, and thereby move the racks 22 and 46 in opposite directions to cause the last pin to be tilted in a direction to force the toe of the shoe firmly against the toe rest and simultaneously the heel supporting arm to be forced away from the toe rest. The connections between the jacking lever 72 and the pinion 64 consist of arms 242 projecting from the hub of the pinion and a pin 244 projecting from the arm 152 between the arms 242.

After a shoe has been clamped in position on the jack, all parts of the mechanism are held in the positions to which they have been moved by the engagement of the locking latch 70 with the tooth segment 68 secured to the shaft 66. To release the mechanism and permit the return of all the various parts to their initial positions, a manually operable plate 246 is pivotally mounted on the upper end of the toe supporting portion of the jack frame (see Figs. 2 and 4) in convenient position to be manipulated by the operator and is connected to the latch 70 by arms 248 extending forwardly on opposite sides of the jack frame, a cross rod 250, and a link 252, pivotally mounted at its upper end on the rod 250 and at its lower end pivotally connected to the forward end of the latch 70. The latch is pressed towards the ratchet segment 68 by means of a spring 254 stretched between the forward end of the latch and the jack frame and upon movement of the plate 246 in a clockwise direction, the latch 70 is lifted and the various parts of the jacking mechanism are permitted to return to their initial positions. Upon release of the ratchet segment 68, the jacking lever 72 is returned to its initial position by means of a spring 256 connecting the arm 152 with the jack frame, and the mechanisms actuated from the lever are returned to the positions indicated in Fig. 14. During the return movement of lever 212, a beveled projection 258 on the lever, see Figs. 5, 13 and 18, engages a downwardly projecting arm of the latch 164 and moves the latch out of engagement with the link 144.

The operation of the jack illustrated in the drawings has been indicated in connection with the description of the construction and arrangement of the various parts, but may be briefly summarized as follows:

With the jack open and with no shoe on the jack, the mechanism for clamping the shoe on the jack is in the position indicated in Figs. 1 to 14. With the parts in this position, the clamping mechanism is locked out of operation and the heel support is free to move towards the toe support. At this time, the racks illustrated in Fig. 14 are out of mesh so that both the upper rack 22, which is connected directly to the heel sup-

porting arm and the lower rack 46, which is connected to the mechanism for tipping the heel pin, are both freely movable. The shoe, after being applied to the last pin on the heel supporting arm, is moved with the arm until the toe of the shoe strikes the toe stop 18. When the toe of the shoe strikes the stop, the stop is moved away from the end plate of the jack and through the connecting links 220, 216 and bell crank lever 218 lifts the locking latch 214. This releases the clamp actuating mechanism which is actuated from the jacking lever 72. Until this latch is lifted, the hand lever cannot be moved by the operator.

As soon as the latch 214 is lifted, the jacking lever 72 can be moved by the operator. As it moves upward to the position indicated in Fig. 15, the floating lever 148 is moved bodily upward, the pin 206 sliding in the slots of the plates 208 and the floating lever pivoting around its pivotal connection with the links 146 which form a portion of the connections for moving the leveling pins and toe grips against the shoe and for locking the grips against outward and downward movement. During this bodily movement of the floating lever 148, the lever 212 is swung about its pivot to the position indicated in Fig. 15, and during this movement of the lever 212, the roll 228 mounted on its lower end presses the rack 22 into mesh with the rack 24 and moves the rack carrying member 26 downwardly to bring the rack 52 into mesh with the rack 46 and pinion 64. This connects the heel and toe supporting portions of the jack and stops further movements of the heel support towards the toe support. Further upward movement of the hand lever 72 to the position indicated in Fig. 16 swings the floating lever 148 around the pin 230 on the lever 148 which is now in engagement with the upper end of the pivoted arm 232 and through the links 146, floating links 138 and links 120 (see Fig. 10) pull the leveling pins in against the shoe. The pins engage the toe grips and move the toe grips in against the shoe. After the pins and grips are pressed against the shoe, continued movement of the floating lever 148 moves the floating link 138 about the connection with the lower ends of the links 120 and through the mechanism illustrated in Figs. 6 and 12, pulls in the wedge 104 and forces the locking member 108 against the lower end of the locking plunger 98 which is raised to cause its notched upper end to engage the slides 90 connected to the levers 80 on which the toe grips are mounted. The side grips are thus locked in position against outward movement and also the carrier 94 in which the locking plunger 98 is mounted, which carrier has been swung to one side or the other about the pivot at the upper end of the carrier by the relative up and down movement of the toe grips when the shoe was placed in position.

As the jacking lever 72 is moved to its final position indicated in Fig. 17, the shaft 180 upon which the cam 178 is fixed, is rocked, the upward movement of the floating lever 148 to permit actuation of the rock shaft being permitted by the outward yielding of the arm 232. When the shaft 180 is rocked, the cam 178 (see Fig. 11) operates on lever 134 (see Fig. 11) which is connected at one end to the toe gage and at the other end through links to the leveling pins. Actuation of the cam serves to draw down the toe gage and also the leveling pins.

Prior to the downward movement of the leveling pins, the pressure of the pins against the shoe

is relieved by the rotation of the notched rods 124 shown in Fig. 10, which rods are rotated from cam 200 (see Fig. 14) which is secured to shaft 66 actuated from the jacking lever 72 and which raises lever 198 connected by link 195 to gear segment 196 meshing with pinions 194 on the ends of the rods 124.

The operations which take place in releasing the shoe have been sufficiently described and a separate summary is believed to be unnecessary.

The nature and scope of the invention having been indicated and a specific embodiment of the several features of the invention having been illustrated and described, what is claimed is:

1. A shoe supporting jack having, in combination, a toe rest, a heel supporting last pin, a support movable towards and from the toe rest on which the last pin is mounted for pivotal movement to press the toe of the shoe against the toe rest, a jacking lever on which the toe rest is mounted, connections between the jacking lever and the last pin acting to tip the last pin to press the toe of the shoe against the toe rest upon a movement of the support for the last pin away from the toe rest, and mechanism mounted on the jacking lever and connected to the support for the last pin for forcing said support away from the toe rest.

2. A shoe supporting jack having, in combination, a toe rest, a heel supporting last pin, a support movable towards and from the toe rest on which the last pin is mounted for pivotal movement to press the toe of the shoe against the toe rest, a jacking lever mounted on the jack, connections from the jacking lever to the last pin for tipping the last pin to press the toe of the shoe against the toe rest, and connections from the jacking lever to the last pin support for forcing the last pin support away from the toe rest.

3. A shoe supporting jack having, in combination, a jacking lever, a heel supporting last pin, a support movable towards and from the toe rest on which the last pin is mounted for pivotal movement to press the toe of the shoe against the toe rest, a jacking lever mounted on the jacking lever, connections from the jacking lever to the last pin acting when actuated to tip the pin and exert a force on the support tending to move the support towards the toe rest, and connections from the jacking lever to the support for moving the support away from the toe rest.

4. A shoe supporting jack having, in combination, a heel support and a toe rest relatively movable towards and from each other, said toe rest comprising toe grips movable towards and from each other to engage the last supported upper of a shoe placed on the jack and shaped to extend around the last supported upper sufficiently to support the toe portion of the shoe at the desired height.

5. A shoe supporting jack having, in combination, a heel support and a toe rest relatively movable towards and from each other, said toe rest comprising separate supports at opposite sides of the shoe relatively movable heightwise of a lasted shoe placed on the jack to compensate for differences in the height of the last at opposite sides of the shoe.

6. A shoe supporting jack having, in combination, a heel support and a toe rest relatively movable towards and from each other, said toe rest comprising toe grips movable towards and from each other to engage the last supported upper of a shoe placed on the jack, the said toe grips being shaped to extend around the last

supported upper sufficiently to support the toe portion of the shoe at the desired height, and being relatively movable heightwise of a lasted shoe placed on the jack to compensate for differences in the height of the last at opposite sides of the shoe.

7. A shoe supporting jack having, in combination, a heel support and a toe rest relatively movable towards and from each other, said toe rest comprising separate supports at opposite sides of the shoe relatively movable heightwise of a lasted shoe placed on the jack to compensate for differences in the height of the last at opposite sides of the shoe, and means for locking said supports in the positions to which they are moved in placing a shoe upon the jack.

8. A shoe supporting jack having, in combination, a heel support and a toe rest relatively movable towards and from each other, said toe rest comprising toe grips movable towards and from each other to engage the last supported upper of a shoe placed on the jack, the said toe grips being shaped to extend around the last supported upper sufficiently to support the toe portion of the shoe at the desired height, and being relatively movable heightwise of a lasted shoe placed on the jack to compensate for differences in the height of the last at opposite sides of the shoe, and means for locking said grips against separation after being moved to engage the last supported upper of a shoe placed on the last and for locking the grips in the heightwise position to which they are moved in placing a shoe on the jack.

9. A shoe supporting jack having, in combination, a heel support and a toe rest relatively movable towards and from each other, said toe rest comprising toe grips movable towards and from each other to engage the last supported upper of a shoe placed on the jack and shaped to extend around the last supported upper sufficiently to support the toe portion of the shoe at the desired height, each grip being pivotally mounted to swing about two axes substantially at right angles to each other, one axis extending lengthwise of a shoe placed on the jack and the other axis extending heightwise of the shoe.

10. A shoe supporting jack having, in combination, a heel support and a toe rest relatively movable towards and from each other, and means for determining the plane transversely of the shoe in which the tread surface of the sole of a shoe supported on the jack will be located comprising leveling devices arranged to engage the under surface of the projecting shoe sole at opposite sides of the shoe.

11. A shoe supporting jack having, in combination, a heel support and a toe rest relatively movable towards and from each other, said heel support comprising a last pin and supporting means therefor permitting lateral tipping movement of the pin as a shoe is placed on the jack, and means for determining the plane transversely of the shoe in which the tread surface of the sole of a shoe supported on the jack will be located comprising leveling devices arranged to engage the under surface of the projecting shoe sole at opposite sides of the shoe.

12. A shoe supporting jack having, in combination, a heel support and a toe rest relatively movable towards and from each other, and yieldingly mounted leveling devices arranged to engage the under surface of the projecting shoe sole at opposite sides of the shoe prior to the engagement of the toe rest by the shoe.

13. A shoe supporting jack having, in combination, a heel support and a toe rest relatively movable towards and from each other, yieldingly mounted leveling devices arranged to engage the under surface of the projecting shoe sole at opposite sides of the shoe prior to the engagement of the toe rest by the shoe, and means for clamping the shoe in position and for withdrawing said leveling devices from engagement with the shoe sole.

14. A shoe supporting jack having, in combination, a heel support and a toe rest relatively movable towards and from each other, and yieldingly mounted leveling devices arranged to engage the under surface of the projecting shoe sole at opposite sides of the shoe prior to the engagement of the toe rest by the shoe, said toe rest comprising separate supports at opposite sides of the shoe relatively movable heightwise of a lasted shoe placed on the jack to compensate for differences in the height of the last at opposite sides of the shoe.

15. A shoe supporting jack having, in combination, a heel support and a toe rest relatively movable towards and from each other, yieldingly mounted leveling devices arranged to engage the under surface of the projecting shoe sole at opposite sides of the shoe prior to the engagement of the toe rest by the shoe, said toe rest comprising separate supports at opposite sides of the shoe relatively movable heightwise of a lasted shoe placed on the jack to compensate for differences in the height of the last at opposite sides of the shoe, and means for locking the supports in the heightwise position to which they are moved in placing a shoe on the jack and for withdrawing said leveling devices from engagement with the shoe sole.

16. A shoe supporting jack having, in combination, a heel support and a toe rest relatively movable towards and from each other, leveling devices located at opposite sides of a shoe placed on the jack arranged to engage the under surface of the projecting shoe sole and being movable towards and from each other and also being movable heightwise of the shoe to permit the shoe after being leveled by said devices to be brought into engagement with the toe rest.

17. A shoe supporting jack having, in combination, a heel support and a toe rest relatively movable towards and from each other, yieldingly mounted leveling devices located at opposite sides of a shoe placed on the jack arranged to engage the under surface of the projecting shoe sole prior to the engagement of the toe rest by the shoe, and being movable towards and from each other, and means for clamping the shoe in position and for withdrawing said devices from engagement with the shoe sole heightwise of the shoe.

18. A shoe supporting jack having, in combination with the other shoe supporting and clamping devices, toe grips movable towards and from each other to engage the last supported upper of a shoe placed on the jack, leveling devices located on opposite sides of a shoe placed on the jack arranged to engage the under surface of the projecting shoe sole and being movable towards and from each other, and connections whereby the toe grips are moved into engagement with the shoe by the movement of the leveling devices towards each other.

19. A shoe supporting jack having, in combination with the other shoe supporting and clamping devices, toe grips movable towards and from each

other to engage the last supported upper of a shoe placed on the jack, leveling devices located on opposite sides of a shoe placed on the jack arranged to engage the under surface of the projecting shoe sole and being movable towards and from each other, a lever mounted on the jack, and connections actuated by the lever for moving the leveling devices towards each other and the toe grips into engagement with the shoe.

10 20. A shoe supporting jack having, in combination with the other shoe supporting and clamping devices, toe grips movable towards and from each other to engage the last supported upper of a shoe placed on the jack, locking devices for said grips, a lever mounted on the jack, and connections actuated by the lever for moving the toe grips into engagement with the shoe and for thereafter actuating the locking devices to lock the grips against separation.

20 21. A shoe supporting jack having, in combination, a heel support and a toe rest relatively movable towards and from each other, a toe gage arranged to be engaged by the toe end of a shoe when a shoe is located longitudinally on the jack by the relative movement of the heel support and toe rest, a lever mounted on the jack, and means actuated by the lever for withdrawing the toe gage heightwise of the shoe and for clamping the shoe in position.

25 22. A shoe supporting jack having, in combination, a heel support and a toe rest relatively movable towards and from each other, a toe gage arranged to be engaged by the toe end of a shoe when the shoe is located longitudinally on the jack by the relative movement of the heel support and toe rest, yieldingly mounted leveling devices located at opposite sides of a shoe placed on the jack and arranged to engage the under surface of the projecting shoe sole prior to the engagement of the toe rest by the shoe and being movable towards and from each other, a lever mounted on the jack, and means actuated by the lever for withdrawing the toe gage and the leveling devices heightwise of the shoe and for clamping the shoe in position.

30 23. A shoe supporting jack having, in combination, a heel support and a toe rest relatively movable towards and from each other, leveling devices located at opposite sides of a shoe placed on the jack arranged to engage the under surface of the projecting shoe sole, a lever mounted on the jack, and connections actuated from the lever for moving the leveling devices towards each other into engagement with the shoe upper, and for thereafter relieving the pressure of the leveling devices against the shoe, and for withdrawing the leveling devices heightwise of the shoe.

35 24. A shoe supporting jack having, in combination, a heel support and a toe rest relatively movable towards and from each other, toe centering grips movable towards and from each other to engage the last supported upper of a shoe placed on the jack, leveling devices located at opposite sides of a shoe placed on the jack arranged to engage the under surface of the projecting shoe sole and being movable towards and from each other, locking devices for the toe grips, a lever mounted on the jack, and connections actuated by the lever for moving the leveling devices towards each other and the toe grips into engagement with the shoe, and during continued movement of the lever for actuating the locking devices to lock the toe grips against separation for relieving the inward

pressure of the leveling devices and for withdrawing the leveling devices heightwise of the shoe.

25. A shoe supporting jack having, in combination, a heel support and a toe rest relatively movable towards and from each other, toe centering grips movable towards and from each other to engage the last supported upper of a shoe placed on the jack, leveling devices located at opposite sides of a shoe placed on the jack arranged to engage the under surface of the projecting shoe sole and being movable towards and from each other, locking devices for the toe grips, a lever mounted on the jack, connections actuated by the lever for moving the leveling devices towards each other and the toe grips into engagement with the shoe, and during continued movement of the lever for actuating the locking devices to lock the toe grips against separation for relieving the inward pressure of the leveling devices and for withdrawing the leveling devices heightwise of the shoe, and means actuated during the final movement of the lever for clamping the shoe in position.

26. A shoe supporting jack having, in combination, a toe rest, a heel supporting last pin, a base rigid with the pin, a block in which the base is mounted to swing about an axis extending in the same general direction but angularly disposed with relation to the axis of the last pin, and a support in which the block is pivotally mounted to tip the last pin in a direction to press the toe of a shoe in the jack against the toe rest.

27. A shoe supporting jack having, in combination, a toe rest, a heel supporting last pin, a base rigid with the pin, a block in which the base is mounted to swing about an axis located to cause a change in the lateral inclination of the last pin as the base is swung, a support in which the block is pivotally mounted to tip the last pin in a direction to press the toe of a shoe in the jack against the toe rest, and a common means for locking the base to the block and for actuating the block to tip the last pin.

28. A shoe supporting jack having, in combination, a toe rest, a heel supporting last pin,

a base rigid with the pin, a block in which the base is mounted to swing about an axis extending in the same general direction but angularly disposed with relation to the axis of the last pin, a support in which the block is pivotally mounted to tip the last pin in a direction to press the toe of a shoe in the jack against the toe rest, and means for locking the base to the block.

10 29. A shoe supporting jack having, in combination, a toe rest, a heel supporting last pin, a base rigid with the pin, a block in which the base is mounted to swing about an axis extending in the same general direction but angularly disposed with relation to the axis of the last pin, a support in which the block is pivotally mounted to tip the last pin in a direction to press the toe of a shoe in the jack against the toe rest, a locking lever mounted in the block arranged to engage the base and lock the base to the block, a jacking lever, and connections from the jacking lever for actuating the locking lever to lock the base to the block and actuate the block to tip the last pin.

25 30. A shoe supporting jack having, in combination, a jack frame, a toe rest mounted on the frame, a heel support, and a heel supporting arm on which the heel support is mounted movable towards and from the toe rest and comprising front and rear portions extending heightwise of a shoe supported on the jack and separated to provide an opening to receive a boot leg or high shoe upper.

35 31. A shoe supporting jack having, in combination, a jack frame, a toe rest mounted on the frame, a heel supporting arm pivotally mounted on the frame to move towards and from the toe rest and comprising front and rear portions extending heightwise of a shoe placed on the jack and separated to provide an opening to receive a boot leg or a high shoe upper, a last pin pivotally mounted on the rear portion of said arm, and mechanism mounted in the frame and in the rear portion of said arm for tipping the last pin in a direction to press the toe of a shoe on the jack against the toe rest.

GARRETT P. S. CROSS.
